UNITED STATES PATENT OFFICE

157,348

SOAP GRATER AND DISPENSER

James H. Crichton, Charlotte, N. C.

Application August 16, 1948, Serial No. 148,136

Term of patent 14 years

(Cl. D4—3)

To all whom it may concern:

Be it known that I, James H. Crichton, a citizen of the United States, residing at Charlotte, in the county of Mecklenburg and State of North Carolina, have invented a new, original, and ornamental Design for a Soap Grater and Dispenser, of which the following is a specification, reference being had to the accompanying drawing, forming part thereof.

I claim:

The ornamental design for a soap grater and dispenser, as shown.

JAMES H. CRICHTON.
